UNITED STATES PATENT OFFICE

2,568,770

METHOD OF MAKING LEATHER STRAPS

Philip J. Shively, Kingsport, Tenn.

Application November 30, 1948, Serial No. 62,723

6 Claims. (Cl. 69—21)

1

The present invention relates to method of making leather straps.

For some purposes, as in a check strap for snubbing the motion of a picker stick in loom operations of the type described and shown in U. S. Patent 1,993,531, it is desirable to employ a leather strap having curved longitudinal edges, one of which is longer than the other. As indicated in said patent, the closed loop of the check strap is made from a strip of leather which is initially cut in arc form so that when the ends are brought together, the sides of the loop slope inwardly in truncated conical fashion. Thus the strap meets the picker stick at an angle approximating that of the stick when it approaches the ends of its usual reciprocating movement.

Leather strips cut initially in arc form are relatively costly as compared to straight strips. In other words, from a given finished skin or hide, a greater number of satisfactory strips could be obtained where the edges are straight than were obtainable where the strips are cut with initially curved edges.

Accordingly, it has been an object of the present invention to provide a leather strap having novel characteristics which improve its usefulness, for example in forming the check strap shown in said Patent 1,993,531. A further object of the invention has been to provide a method by which leather straps having these characteristics may be successfully and economically produced. Other objects and beneficial results contemplated in the use of said leather strap and in practicing the method of making the same as hereinafter disclosed and claimed will appear from the following description of one form of said strap and an example of said method and from the drawings appended thereto. It will be understood that the invention is capable of many different embodiments and that the following description is not intended to be exhaustive or limiting, but on the contrary, is designed to instruct others in the principles of the invention and to illustrate and explain it so that they will be enabled to modify and adapt it for various uses and conditions.

As shown in the accompanying drawings:

Figure 1 is a top plan view of a tanned, curried, and finished ox hide in substantially flat condition showing a series of longitudinally extending cuts or slits substantially parallel with, and on, the left side of, the central longitudinal axial line of the hide and another series of cuts or slits substantially parallel and on the right side of

ranged at right angles to said central longitudinal axial line of the hide;

Figure 2 is a top plan view of a leather strip produced by parallel slits or cuts made as indicated in Figure 1 in a direction parallel with the central longitudinal axial line of the hide;

Figure 3 is an enlarged view of a portion of the strip shown in Figure 2 and indicating a more dense fibrous structure at one edge and a less dense fibrous structure at the opposite edge;

Figure 4 is a transverse section on the line 4—4 of Figure 3 and indicating the variation in density of the fibrous structure referred to in connection with the foregoing description of Figure 3;

Figure 5 is an enlarged view of a portion of one of the leather strips produced by making the cuts or slits in a direction at right angles to the central longitudinal axial line of the hide, and indicating a greater density of the fibrous structure at one end of the strip than at the other end;

Figure 6 is a longitudinal section on the line 6—6 of Figure 5 and indicating a more dense fibrous structure at one end and a less dense structure at the other end of said strip;

Figure 7 is a top plan view of a leather strap according to the invention;

Figure 8 is a transverse section on the line 8—8 of Figure 7;

Figure 9 is a front elevation illustrating one form of roller mechanism appropriate for producing a leather strap of the shape indicated in Figure 7;

Figure 10 is a top plan view of the mechanism illustrated in Figure 9 and showing a strip of leather in process of passing between the rolls thereof;

Figure 11 is a front elevation of a strip in clamps which can be moved apart with controlled tensioning whereby the leather strip, e. g. such as is shown in Figure 3, may be manipulated to assume the arc shape shown in Figure 7 by application of tension longitudinally thereof either with or without the rolling operation illustrated in Figures 9 and 10; and

Figure 12 is an isometric view of a strap such as that of Figure 7 after bringing the ends over one another to form a loop.

Leather straps embodying the invention herein described and claimed are prepared from strips of leather cut from hides, of which the hide 10, Figure 1 represents a typical example more specifically a usual ox-hide which has been tanned, curried, and finished and spread out to a more or less flat condition. In the finished hide 10,

the component fibers are relatively shorter and more densely arranged in the area near the backbone and are longer and of gradually diminishing density toward the belly portion of the hide.

The best leather for the industrial purposes here contemplated occurs in that portion of the hide extending from the tail approximately to the shoulder and to a distance of approximately 20" on either side of the central longitudinal or backbone line of the hide. To obtain strips of any desired width from this general preferred area, for example, the hide 10 is cut or slit along the lines 11 and 12 to form strips of leather 13. Strips 16 may also be cut having a lesser natural curvature satisfactory for various purposes by cutting the indicated portion of the hide along the lines 14 and 15.

As indicated in Figure 1, the cuts or slits 11 are substantially parallel to the longitudinal axial line of the hide whereas the slits or cuts 14 are perpendicular thereto. In either case, the longitudinal edges of each of the strips 13 and 16 are substantially straight and parallel when cut from a flat hide.

In the case of strips 13, due to characteristics of the fibrous structure of hides, those parts of said strips which are derived from portions of the hide nearer to the line of the backbone are of greater density than those parts of the strips derived from portions of the hide more remote therefrom; and as shown in Figures 2, 3, and 4, each strip 13 is of a more dense fibrous structure at its right hand edge than at its left hand edge. As shown in Figures 5 and 6 the strips 16 are of greater fibrous density and are made up of shorter fibers at their left hand ends, that is nearer to the line of the backbone, than at their right hand or outer ends.

A leather strap 17, particularly suitable for use in forming check straps of the type illustrated in Patent No. 1,993,531 for example, is conveniently produced from one of said strips 13. For this purpose, a strip 13 is subjected to forces which cause elongation of the one side or edge portion in relation to the other side or edge portion thereof. As indicated in Figure 10, in a hand procedure, one end of strip 13 is secured in a clamp 18; and that portion of strip 13 adjacent to the right hand edge 19 is elongated by tension applied in any suitable manner, for example through a clamp 20 which is attached to the strap in an oblique position and subsequently pulled to rectangular relation. Thus, right hand edge portions of strip 13, as viewed in Figure 10, are elongated in relation to the left hand edge portions thereof. The result is that the right hand edge 19 assumes a convexly curved outline whereas the edge 22 assumes a concavely curved outline substantially parallel to that of 19. Even if tension is applied uniformly over the width of the strip (e. g. pivotally to the clamps 18 and/or 20), a curvature will be developed, since the material on opposite lateral portions has different resistance to tensile stress.

In an alternative procedure the check strap, as 17, Figure 7, is produced by passing a strip 13 between positively driven rollers 23 and 24, Figures 9 and 10. Whereas the roller surface of roll 23 is in this case shown cylindrical, that of roll 24 is conical, with its greater diameter at the right side, as viewed in Figure 9, and its smaller dimension at the left hand side. Holes 25 and 26 may be punched or cut near the ends for attaching bolts.

To attain elongation of edge portion 19 by

means of rolls 23—24, said strip 13 is passed between said rolls with the edge 19 engaged in the relatively narrow space between said rolls and the edge 22 in the relatively wider portion of said space. In other words, the edge 19, representing a portion of less dense fibrous structure of the strip 13, is subjected to a greater compressive effect on its thickness and a greater tensile stress along its length than is applied to the more dense portion of the strip 13. This differential compression and tension, applied progressively as the strip 13 is moved between said rolls when they are being driven, causes that edge portion 19 of said strip to be compressed and elongated in relation to edge 22 so that, in the finished product or strap 17, Figures 7 and 8, the strap is convexly curved.

The above described rolling operation may be employed with or without the simultaneous application of tension produced by pulling on a portion of the strip in a direction indicated by the arrow, for example by means such as those shown in Figure 11, or other suitable means including pulling by hand.

Although the steps of procedure above described are applied to strips, as 13, it is contemplated that a leather band product similar in its curvature to the strap 17 and useful for similar purposes may be obtained by similarly processing strips which have been cut from the hide on lines oblique or perpendicular to the axial line of the backbone region thereof, provided that the area of each strip is a portion of the hide which was distorted laterally when the hide was flattened from the shape it had on the animal. Such strips cut perpendicular are shown at 16. In this case, the elongated edge or lateral area of the strip should be that toward a line perpendicular to the longitudinal axis of the hide at a point approximately midway between the shoulder and the base of the tail. The shorter relatively less stretched part will be at the fore edge or the rear edge according to the side of the perpendicular line from which it came, thus taking advantage of the natural curvature of the hide which has been pressed out during tanning and other treatments but I have found to be still latent in the strips. Stated in another way, the part of the hide included in the strip 13 or 16 or the like, when on the animal had a three-dimensional curvature with its center of curvature displaced laterally from the area included in the strip, and advantageously from a mid-part of the strip length. The application of pressure and/or tension along one edge or lateral portion effects an elongation of that portion in relation to the opposite edge and will release such latent curvature and produce a strap of arc-shaped form not dissimilar in appearance to that shown in Figure 7.

It will be apparent from the foregoing description and from Figures 9, 10, and 11 that the curvature can be controlled by the amount of pressure and/or tension, which can be varied, not only as to any desired portion of the strip but also from one portion to another. For example as indicated in Figure 11, by changing the angular relation of clamps 18 and 20, or by engaging a greater or less width from the edge tension may be applied to a greater or less width of the strip. If the clamps 18 and 20 are not at fixed angular relation, but are pivotally mounted, the resulting strap will have its latent curvature more fully developed, and all across its width will have about the same resistance to stretch.

Also, all or any desired edge portion of the strip 13 can be subjected to the compressing action of rolls 23 and 24 and/or to tension by devices as shown, or by other suitable means.

In processing strips 13 or 16 by combined action of pressure rolls, and direct pull, the attendant tension exerted lengthwise of the strip by the operator serves to control, in part, the degree of curvature of the arc produced. The degree of differential stretch produced by the rolls depends upon the conical form of one or both of the rolls 23, 24 and the differential compression by the angular relation of their faces. Each of these contributes to a certain extent to the curvature given the product strap. These effects of the rolls may be varied to meet different conditions. Thus, by regulating and controlling the amount and location of tension and/or compression the method of the present invention enables the operator to control the degree of arc produced upon the initially straight edge strips 13 and 16 within limits, of course, imposed by the structural character of the strips. Thus the strip is given the desired curvature to form a truncated conical loop; and, if the maximum stretch is along the side in which the leather has been more compressed or less stretched in its prior treatment, its latent curvature is developed and all parts of the strip are brought more nearly into balance with respect to resistance to stretch in a truncated conical loop.

A leather strap derived from the sources and processed as above described presents a product of arc shape produced by readjustment or redistribution of the natural fiber as distinguished from one produced by initially cutting the leather to arc shape. This results in a more uniformly strong and durable piece of leather which when used as a check strap adjusts itself to a given picker stick snubbing application more effectively and wears substantially longer in that use than is the case with known forms of straps. In addition to advantageous performance, the above described product enables the manufacturer to cut more straps from the same area of leather than would be possible if the straps were cut initially in arc form and is therefore more economical than known products for a similar purpose.

Various embodiments may be made of the above invention and changes might be made in the embodiments and examples of procedure above set forth. It will also be apparent from the foregoing that a leather strap made in accordance with the method hereinabove described is well adapted to attain the ends and objects hereinbefore set forth and to be economically manufactured since both the article and the method of making it are suited to usual production methods and are susceptible to a substantial latitude of variations as may be desirable in adapting the invention to different applications.

I claim:

1. Method of making a leather strip which includes the steps of cutting hide leather material from the region of the back, upper belly and hind quarters along lines substantially parallel to the central longitudinal axial line of the backbone region of the hide to form a leather strip, applying pressure and tension simultaneously thereto in a direction to stretch that portion of said strip

which was more remote from said longitudinal axial line of the hide more than the less remote portion.

2. Method of making a leather strip which includes the steps of cutting hide leather material from the region of the back, upper belly and hind quarters along lines substantially parallel to the central longitudinal axial line of the backbone region of the hide to form a leather strip and applying differential pressure over the width of the strip to elongate that portion of said strip which was more remote from said longitudinal axial line more than that which was closer.

3. Method of making a leather strip which includes the steps of cutting hide leather material from the region of the back, upper belly and hind quarters along lines substantially parallel to the central longitudinal axial line of the backbone region of the hide to form a leather strip and applying differential pressure over the width of the strip greater in that portion which was more remote from said longitudinal axial line than in that which was closer and progressively lengthwise of said strip.

4. Method of making a leather strip which includes the steps of cutting a strip from a previously flattened tanned hide and from a portion thereof, which, when on the animal, had substantial three-dimensional curvature, said cutting being along lines transverse to the direction of lateral distortion of the tanned hide when flattened from said three-dimensional curvature, and subjecting said strip to rolling contact pressure across its area in a direction to develop the latent curvature in the strip by relieving the stress imposed in flattening the hide and thereby to lengthen one edge of the strip in relation to the other.

5. Method of making a leather strip which includes the steps of cutting a strip of hide leather material which has greater fibrous density at one edge and less fibrous density at the other, and subjecting said strip rolling contact compression which varies progressively transversely across said strip being greater along the edge of less fibrous density.

6. Method of making a leather strip which includes the steps of slitting hide leather material to form a strip and applying a compressive force in the direction of its thickness while subjecting said strip to tension longitudinally thereof, said compressive and tension effects being greater at one lateral edge than at the opposite lateral edge thereof.
